UNITED STATES PATENT OFFICE

2,572,654

CAMBER ADJUSTING TOOL

Frederik Nielsen, Quincy, Mass.

Application January 31, 1947, Serial No. 725,529

2 Claims. (Cl. 81—15)

1

This invention relates to mechanism for adjusting the camber of knee action vehicle wheels and by which the knuckle may be deflected without damage to any of the parts.

This application is a continuation-in-part of my application Serial No. 503,184, filed September 21, 1943, for Camber Adjusting Tool, now Patent No. 2,425,556 granted August 12, 1947.

The present invention relates to such a mechanism which can be actuated from a convenient position away from the knee action, where it is fully accessible, and which is particularly suitable for power actuation.

For a complete understanding of the mechanism, reference may be had to the accompanying drawings in which

Figure 1 is a fragmentary perspective view showing the mechanism embodying the invention in position for operation.

Figure 2 is a perspective view showing a modified mechanism.

Figure 3 is a sectional view to a larger scale on line 3—3 of Figure 1.

Figure 4 is an exploded perspective view showing a further modification.

Figures 5 and 6 are perspective views showing still further modifications.

In Figures 1 through 6 there is illustrated a camber adjusting mechanism wherein the bending of the knuckle support is accomplished by rocking a forked member which straddles the upper portion of the knuckle support A. Referring first to Figures 1 and 3, a fork 1 may be provided with a tubular or other type of handle 2 extending backwardly from the juncture between the branches of the fork and substantially parallel thereto, the branches of the fork presenting free extremities spaced substantially greater than the thickness of the knuckle support to engage on opposite sides thereof at positions spaced therealong which forms a rock shaft and near its outer end it may be secured to a rectangular yoke member 3 having an extension 4 journaled in a stand 5. An actuating bar 6 may be thrust through the yoke 3 and then turned so as to rock the shaft 2, causing the transverse jaws of the member 1 to so engage and apply pressure to the upper portion of the knuckle support that this knuckle support may be deflected from the solid line position shown in Figure 3 to the dotted line position in which the desired adjustment has been effected. Where but a single pair of bending elements, such as the branches of the fork 1 which is twisted thereagainst, is employed, there is an unbalanced force tending to

2

rock the axial member laterally of the vehicle. Consequently, in Figure 1, means is shown for taking the thrust pressure exerted on the upper portion of the knuckle support so that no injury to other parts of the mechanism may result. In many cases, however, no such thrust-taking means may be found necessary. This thrust-taking means, as shown in Figure 1, may comprise a second fork 10 straddling the lower portion of the knuckle support beneath the knuckle and journaled for rocking motion about its longitudinal axis as by the trunnion 11 carried thereby, and resting in a notch 12 in the upper portion of a stand 15. The fork 10 is provided with a lateral extension 16 through which may be passed an abutment screw 17. Thus, as the left-hand end of the bar 6, as viewed in Figure 1, is forced downwardly, the lateral extension 16 tends to be depressed, the limit of such depression being fixed by the engagement of the screw 17 on the floor or ground.

In Figure 2 a modification is shown in which the shaft 2 is provided with a laterally extended arm 18 against which bears one end of a hydraulic power cylinder 19, the other end of which engages a yoke 90 hooked under the arm 18 of the lower fork 10, both forks having trunnions journaled in a common stand 5a. Admission of pressure to the cylinder 19 will act to rock the shaft 2 counterclockwise.

In Figures 4 and 5 arrangements of mechanism similar to that shown in Figure 1 are illustrated, but wherein the camber adjusting force is exerted by hydraulic mechanism as in Figure 2. Referring to Figure 4, the upper fork member 20 is provided at its rear end with a journal 21 which may engage in a selected one of a plurality of journal openings 22 at the upper end of a strip 23, the journal 21 extending through a vertical slot 24 in a stand 25 supported on the floor or ground. A second forked member 26 corresponding to the forked member 10 shown in Figure 1, is provided with an outer journal 27 which also extends through the slot 24 and is journaled in any one of the journal openings 28 at the lower end of the strip 23. The forked members 20 and 26 are provided with lateral arms 30 and 31, respectively, and means are provided by which these fork members are rocked in opposite directions to produce the camber adjustment.

In Figure 4 an arrangement is shown by which the upper fork member 20 is turned counterclockwise viewed from its outer end and the lower member 26 is turned clockwise. For this purpose a hydraulic cylinder 32 having its piston

bearing against the under face of the arm 31 is supported by a loop member 33 which passes over the outer end of the arm 30. When the hydraulic mechanism 32 is expanded, the arm 31 is forced upwardly and the loop 33 is lowered, forcing the arm 30 downwardly. Thus the desired relative rocking action of the two forks is accomplished.

In Figure 5 an arrangement is shown by which the upper fork member is rocked clockwise and the lower forked member rocked counterclockwise. In this arrangement the hydraulic cylinder mechanism 37 is arranged directly between the upper arm 30 and the lower arm 31 so that when it is expanded the upper arm is rocked upwardly and the lower arm rocked downwardly. It should be understood, however, that this motion is relative. Commonly the upper arm would have the larger motion because the camber adjustment takes place in the upper portion of the knuckle support.

In Figure 6 a modification is shown in which the shank portions 40 of a pair of forks 41, the outer ends of which are journaled in a link 42, are provided with arms 43 between the outer ends of which is carried a hydraulic cylinder 44. The forked inner end portions are spaced apart to engage against lengthwise spaced portions of the knee action support of the knuckle. Separation of the outer ends of the arms 43 by the introduction of pressure into the cylinder 44 will act to twist the forks 41 in opposite directions and thus produce the desired bending action on the knuckle support which is engaged between these forks.

From the foregoing description of certain embodiments of this invention, it should be evident to those skilled in the art that various other changes and modifications might be made without departing from the spirit or scope of this invention.

I claim:

1. A mechanism of the class described, comprising a pair of elongated members each having a forked extremity, the branches of the fork extending substantially parallel to the length of its member and spaced to straddle the knuckle support of a knee action mechanism, the pair of members being spaced lengthwise of said support, and means for turning said members relatively about axes lengthwise thereof in opposite directions.
  2. A mechanism of the class described, comprising a pair of elongated members each having a forked extremity, the branches of the fork extending substantially parallel to the length of its member and spaced to straddle the knuckle support of a knee action mechanism, an arm secured to each of said members spaced from said forks, and means engaging said arms for turning said members relatively about their respective lengthwise axes in opposite directions.
